UNITED STATES PATENT OFFICE.

GEORGE L. MURRAY AND ASHMORE W. CREELMAN, OF BIG SANDY, MONTANA.

PLUNGE-BUCKET WELL-DIGGER.

1,117,424.

Specification of Letters Patent. Patented Nov. 17, 1914.

Application filed March 3, 1911. Serial No. 612,132.

To all whom it may concern:

Be it known that we, GEORGE L. MURRAY and ASHMORE W. CREELMAN, citizens of the United States, residing at Big Sandy, county of Chouteau, and State of Montana, have invented certain new and useful Improvements in Plunge-Bucket Well-Diggers, of which the following is a specification.

This invention relates to plunge bucket 10 well diggers.

Our object is the provision of a simple, strong and durable well digging tool which may be easily operated by hand and will rapidly work its way downward even in 15 stiff clays.

The invention consists of a cylindrical, tubular member provided at its lower end with a circular cleaving edge, a wooden bushing secured within the tubular member 20 above the cleaving edge, and a flap valve, combined in the manner hereinafter set forth.

In the accompanying drawings:—Figure 1 is a vertical section, the same being broken away; and Fig. 2 is a cross section on line 25 2—2, Fig. 1.

The body of the tool 1 is tubular and of suitable length and diameter, having its lower end sharpened to provide the annular edge or knife 2, above which is an internal 30 fillet, preferably a block of wood, 3 having a conical interior 4, the lower end 5 of the fillet terminating a short distance, preferably less than an inch, short of the lower or cutting edge 2. The body 1 constitutes a 35 bucket or chamber 6 above the fillet 3 and there is provided a suitable valve 7 adapted to open upwardly into said chamber and to close the upper open end 8 of the conical bore of the fillet 3. In the upper part of 40 the body 1 is a coupling 9 which has external screw-threads by which it is connected at 10 to the said body, and has internal screw-threads 11 with which engage screw-threads on a pipe 12 of suitable length 45 which is preferably provided with a bail 13 at its upper end and is open throughout its length. To the bail is secured a rope 14 by which the tool may be reciprocated up and down. The lower end of the coupling 9 is 50 internally coned to facilitate the flow of the disintegrated earth up into the stem 12 and to prevent it from clogging. The upper end of the coupling 9 is externally coned to facilitate withdrawal of the tool from the 55 well.

The hole having been started in the ground, water is run into the said hole and finds its way to the cutting edge 2 at the bottom. The digger is then raised a suitable distance, say a foot or so, and dropped, 60 whereupon the cutting edge 2 sinks into the soil which has been softened by the water and a core of soil, gravel, sand or clay which is cut by the edge 2 passes up into the conical interior 4. Upon raising the digger, the 65 previously cut core loosens and falls, chiefly by suction. Upon again dropping the digger, the previously cut core, mingled with, and more or less softened and disintegrated by the water, is forced up through the end 70 70 past the valve 7, which opens to permit the passage thereof, and flows into the containing chamber or bucket 6. Upon again lifting the digger, the weight of the material in the bucket 6 causes the valve 7 to close. Successive reciprocations continue to cause cores to be cut and disintegrated and forced up 75 into the bucket 6 and pipe 12 until the latter is suitably filled to its top, whereupon the tool is hoisted to the surface and emptied. 80 Any overflowing water passes up through the tubular stem 12 and out over the outer end thereof and back into the well.

We have found in practice that with a body or barrel 1 of say four inches in diameter and about a foot in length and a stem 12 of about eight feet in length and two inches in diameter, an able-bodied man working the device by hand, can cut down through stiff clay at the rate of about ten feet an hour. 85 90

Having thus described our invention, what we claim as new and desire to secure by Letters Patent, is:—

A device of the character described comprising a cylindrical tubular member provided at the lower end with a circular cleaving edge, a wooden bushing secured within the end of said tubular member above the cleaving edge, said bushing being provided with an upwardly tapering passage therethrough, and a flap valve normally closing the inner opening of said passage. 95 100

In testimony whereof, we hereunto affix our signatures in presence of two witnesses.

GEORGE L. MURRAY.
ASHMORE W. CREELMAN.
